CLAIM

The ornamental design for a spray head for shower as shown and described.

DESCRIPTION

1. Spray head for shower

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Enlarged

Novelty is claimed in the features of shape and configuration of the spray head for shower shown in the accompanying drawings; the broken lines shown in the drawings represent portions of the spray head for shower that form no part of the claimed design; Fig. 1.1 is a front, left and top side perspective view of a spray head for shower showing our new design; Fig. 1.2 is a rear, right and bottom side perspective view thereof; Fig. 1.3 is a front elevation view thereof; Fig. 1.4 is a rear elevation view thereof; Fig. 1.5 is a left side elevation view thereof; Fig. 1.6 is a right side elevation view thereof; Fig. 1.7 is a top plan view thereof; Fig. 1.8 is a bottom plan view thereof; Fig. 1.9 is an enlarged view of the portion marked '9' of Fig. 1.1; Fig. 1.10 is an enlarged view

(Continued)

of the portion marked '10' of fig. 1.2; and Fig. 1.11 is an enlarged view of the portion marked '11' of fig. 1.2.
